(57) **CLAIM**

The ornamental design for a sensory body sock, as shown and described.

DESCRIPTION

FIG. 1 is a front elevational view of the sensory body sock showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front perspective view thereof, shown in an in-use configuration.

The broken lines in the figures represent the claimed stitching of the sensory body sock.

The dotted lines depicting a man in FIG. 7 illustrate environmental matter, and form no part of the claimed design.
